SPOOL-MAKING APPARATUS

John A. Johnson, Woodhaven, N. Y.

Application October 15, 1936, Serial No. 105,686

34 Claims. (Cl. 113—1)

This invention relates to apparatus for making spools of sheet metal particularly used for carrying a strand or web of material, such as adhesive medicated tape, wound upon the core of the spool, and it is the principal object of the invention to provide apparatus of this character which is compact and entirely automatic in operation.

It is another object of the invention to actuate all of the operating devices of the apparatus from a single drive shaft.

It is a further object of the invention to prevent the feeding of flanges to the apparatus should there be no core present to be assembled with said flanges, thereby eliminating the waste of material and prevent damaging the operative parts of the apparatus.

It is a still further object of the invention to provide the adjustment of the operative parts of the apparatus to permit the making of spools of different lengths and diameters.

Another object of the invention is to provide means to positively feed flanges and cores to the assembling mechanism of the apparatus.

A further object of the invention is to provide means to simultaneously secure flanges to the opposite end portions of a core to form a spool.

A still further object of the invention is to provide means to form an inwardly extending tongue in the core of an assembled spool for anchoring the web to the core.

Another still further object of the invention is to provide means to maintain the flanges engaged on the opposite end portions of a core at a predetermined distance apart and permit longitudinal movement of the flanges and core with the flanges spaced apart at said predetermined distance during the securing of the flanges to the core.

Another still further object of the invention is to provide means to maintain the flanges on a turret during the rotation of the turret from one station to another station prior to the securing of the flanges on the core.

Further objects and advantages of the invention will hereinafter be more fully described in connection with the accompanying drawings.

The embodiment of the invention comprises a rotatable turret carrying a series of radially extending horns which are adapted to be intermittently positioned to successive means to engage a spool flange on the horns, engage a spool core on the horns with one end portion of the core engaging the flange previously engaged on the horns, engage a second spool flange on the op-

posite end portion of the core previously engaged on the horns, simultaneously crimp the opposite end portions of the core with the flanges to form a spool, and transfer the formed spool to a horn of a series of horns carried by a second turret actuated by the rotation of the first turret to position the spools on the horns thereof relative to means to form a tongue in the cores of the spools and eject the spools having tongues in the cores thereof from the horns of the second turret. The means to engage the first and second spool flanges on the horns comprises a plunger reciprocating relative to a flange support and adapted to transfer and engage a flange on a horn positioned relative to the flange support. The plunger for engaging the second flange is arranged with means to flare the outer end of the core engaged on the horn with the first flange subsequently to the engaging of the second flange on the outer end portion of the core to prevent the second flange from being thrown off the horns by centrifugal force created by the rotation of the turret. The means to engage a core on the horns comprises a series of reciprocatory fingers to engage and intermittently advance a plurality of cores toward the turret and engage the first core on a horn positioned relative to said means. Means are interposed between predetermined cores being fed to the turret and means to feed flanges to the flange support whereby the absence of cores at predetermined distances from the turret will prevent the feeding of the flanges to the flange support and the engaging of the flanges by the plungers onto the horns. The means to crimp the opposite ends of the core with the flanges comprises a reciprocatory die to engage the outer end of the core and the second flange and force the inner end of the core and the first flange into engagement with a die arranged on the horns, whereby both ends of the core are secured simultaneously to the flanges. The second turret is actuated by the rotation of the first turret to position one of its horns in alignment with the horn of the first turret having a formed spool thereon and relative to reciprocating means to transfer said spool from the first turret to the second turret, position another of its horns having a spool thereon relative to punch mechanism to form the tongue in the core thereof, and position the other horn carrying a spool arranged with a tongue relative to a reciprocatory arm to engage and strip said spool from said other horn, the spools on the horns of the second turret traveling from the punch mechanism to the stripper arm being partially moved toward

45

55

the free ends of the horns by a cam for engagement with the stripper arm.

In the drawings accompanying and forming a part of this application, Figure 1 is a side elevational view of the apparatus constituting the embodiment of this invention.

Figure 2 is a plan view of the apparatus looking at the top of Figure 1.

Figure 3 is a fragmentary elevational view, partly in section and on an enlarged scale, of the series of reciprocatory fingers for advancing spool cores toward the first turret and actuating means therefor, and showing a core being engaged on a horn of said turret.

Figure 4 is a plan view of the rear portion of the series of fingers showing in full lines the advanced position of the fingers and in dotted lines the initial position of said fingers.

Figure 5 is an end elevational view of the apparatus looking at the left of Figure 3 and showing the means interposed between predetermined cores and the means to feed flanges to the flange supports in normal position to prevent the feeding of flanges, and separable support for the cores being advanced by the reciprocatory fingers with a portion of said support being shown in separated position in dotted lines.

Figure 6 is a fragmentary view of the controlling means for the flange feeding means showing said controlling means being actuated by a core to position to permit the feeding of flanges.

Figure 7 is a plan view, on an enlarged scale, of the first rotatable turret and the means at the successive stations of the horns of said turret for assembling spools and reciprocating means for transferring formed spools from the first turret to the second turret.

Figure 8 is a fragmentary view of the reciprocating means to transfer the formed spool from the horns of the first turret to the horns of the second turret, and showing said means in position engaging a spool carried by a horn of the first turret with a horn of the second turret in position to receive said spool.

Figure 9 is a fragmentary view of a horn on the second turret showing a spool having the tongue therein being engaged and moved toward the free end of the horn by the cam in position to be engaged by the stripper arm.

Figure 10 is a perspective view of the reciprocating means for transferring the formed spools from the first turret to the second turret.

Figure 11 is a sectional view, on an enlarged scale, taken substantially on the line 11-11 of Figure 2 looking in the direction of the arrows to show the actuating means for the first turret, the structure of the horns of the first turret, the positioning of a core on a horn of the first turret in engagement with a flange on said horn, and the means for crimping the opposite ends of the core with the flanges, and with the opposite end portions of the apparatus broken away.

Figure 12 is a sectional view, on an enlarged scale, taken substantially on the line 12-12 of Figure 2 looking in the direction of the arrows and showing the means to engage the flanges on the horns of the first turret.

Figure 13 is a fragmentary view of the plunger in section for engaging the second flange on the outer end of the core and showing the means for flaring the outer end of the core.

Figure 14 is a sectional view, on an enlarged scale, taken on the line 14-14 of Figure 2 looking in the direction of the arrows to show means adapted to engage opposite portions of the core

prior to engagement of the reciprocatory die with the outer end of the core to maintain the flanges a predetermined distance apart during the crimping of the opposite ends of the core with the flanges.

Figure 15 is a fragmentary view, partly in section, showing the relative positions of the core engaging means shown in Figure 14 and the reciprocatory die prior to the engaging of the core by said means and the crimping of the core with the flanges, as shown in Figure 11.

Figure 16 is a fragmentary view of the punch mechanism for forming a tongue in the core of a formed spool and showing the mechanism in tongue forming position in dotted lines.

Figure 17 is a fragmentary view of a partially formed spool prior to the operation of the reciprocatory die.

Figure 18 is a fragmentary view of one end of a spool showing the initial crimping of an end of the core with a flange.

Figure 19 is a view similar to Figure 18 showing the final crimping of an end of the core with a flange.

Figure 20 is a front elevational view of a pocket for positioning a flange relative to the plungers for engaging the flange on the horns; and

Figure 21 is a perspective view of a slide for feeding flanges from a hopper to the pocket shown in Figure 20.

In carrying out the invention illustrated in the accompanying drawings the operative parts are mounted on a suitable framework comprising a table T supported from a base B by standards S, and said operative parts being actuated from a crank shaft 22 rotatably mounted to extend transversely of the table T at the opposite end portions in bearings of a yoke shaped bracket 23 fixed to the table T and supported by a standard S. Said crank shaft 22 is adapted to be operatively connected to a source of power, such as an electric motor, not shown, by a belt adapted to be engaged on a pulley 24 loosely mounted on an end portion of the crank shaft extending from a bearing therefor and adapted to be connected to the crank shaft by a clutch member 25 rotatable with and slidable on said crank shaft and actuated into and out of engagement with the hub of the pulley by a lever 26 pivotally mounted in a bifurcation 27 arranged on the standard S below the bracket 23. Said lever 26 has an intermediate circular portion 28 encircling the clutch member and arranged with pins to engage an annular groove in the clutch member, as at 29 in Figure 2, to permit rotation of the clutch member with the crank shaft 22. The reciprocatory die for securing the core to the flanges is actuated directly from the crank shaft as hereinafter described and the remaining operative parts of the apparatus are actuated from a shaft 30 rotatably mounted in bearings of hangers 31 suspended from the table T to support the shaft longitudinally of the apparatus between the table T and base B. One end of the shaft 30 is arranged with a bevelled gear 32 fixed to the shaft and meshing with a corresponding bevelled gear 33 fixedly mounted on an intermediate portion of a shaft 34 rotatably supported at the opposite ends in bearings 35 arranged in the legs of the standard S below the bearings of bracket 23. The shaft 34 is driven from the crank shaft 22 through gears 36 fixed to the ends of the shafts 22 and 34 meshing with each other and enclosed in a casing 37 mounted on the framework of the apparatus to prevent an accumulation of foreign

matter about said gear and injury to the operator of the apparatus.

A series of supports in the form of horns 38 having one end reduced, as at 39, and engaged in a socket of a corresponding series of socket members 40 arranged with a shank portion 41 engaged in an opening of a series of openings 42 arranged in the sides of a head 43 releasably mounted on a turret 44 rotatably mounted in vertically aligned bearings 45 arranged in the table T on the longitudinal axis and intermediate the ends thereof. The horns 38 are releasably retained in the socket members 40 by set screws 46 (Figure 12) screw threaded in the socket members to abut the reduced ends 39 of the horns so that the horns may readily be replaced by horns adapted to support spool cores of different lengths and diameters. The outer end of each horn is reduced to approximately the diameter of the core of the spool desired to be made, as at 59, and the shoulder formed by said outer reduced portion 59 and the body 38 of the horn is arranged with an annular recess or groove 60 to form a die for crimping one end of the core to a flange, which operation will be more fully described hereinafter. Each horn is arranged with stripper mechanism comprising an annular member or sleeve 73 encircling the horn body 38 and slidably mounted on headed pins 74 fixed in and projecting longitudinally from the socket member 40 with the annular member being yieldingly urged toward the reduced outer end 59 of the horn by springs compressed between the outer end of the annular member and a recess in the socket member, as clearly shown at 75 in Figure 11. The outward movement of the annular member 73 toward the horn end 59 is limited by the heads of the pins engaging the inner end of the annular member, as shown in the left hand horn of Figure 11. The operation of the stripper mechanism will be more fully described hereinafter. The socket members 40 are adjustable in the head 43 to vary the extent said members extend from the head and said members 40 are retained in adjusted position by set screws screw-threaded in the head to abut the shank portions 41 and arranged with lock nuts, as at 47, and a section of each shank portion adjacent the socket is screw threaded for the engagement of a locking nut 48 adapted to be engaged on the shank abutting the side of the head and secured in such position by a clamping plate 49 releasably mounted on the head 43 by screws 50.

The head 43 is adjustably mounted on the turret 44 to properly position the horns relative to the operative parts of the apparatus by clamping the head to an annular shoulder 51 arranged on the turret. The head 43 is clamped to the shoulder 51 by a nut 52 screw threaded on a reduced extremity of the turret extending above the head and adapted to abut a washer 53 engaged on said reduced extremity of the turret and abutting a collar 54 keyed to an intermediate reduced portion of the turret, as shown at 55 in Figure 11, and having an annular exterior shoulder adapted to abut the head 43. The head is locked in adjusted position by an annular member 56 arranged with a shoulder in the bore thereof to form a lock joint with the shoulder 50 of the collar 54, as at 57, and the annular member is secured to the head by bolts 58 engaged in said member and the head. By this construction it is possible to maintain the adjusted position of the head relative to the collar 54 while the collar with the head and associated horns con-

nected thereto are removed from the turret to be replaced by a head having a different number or type of horns, and the replaced head may again be positioned on the turret without requiring readjustment of the head relative to the annular member 56. In the present instance, the head is of octagonal shape with the openings 42 for the socket members 40 in each lateral face of the head.

The turret 44 is intermittently rotated to present each horn 38 to eight stations a, b, c, d, e, f, g, h, by a Geneva mechanism comprising a wheel 61 keyed to the turret 44, as at 62 in Figure 11, and arranged with eight recesses 63 equidistantly spaced about the periphery and extended radially inward, with the portions of the periphery of the wheel 61 between the recesses being of curved or convexed form, as at 64. The wheel 61 is intermittently actuated from the longitudinal shaft 30 by rollers 65 rotatably mounted on pins 66 fixed in and extending perpendicularly from a disk 67 fixed to a countershaft 68 rotatably mounted in a bearing boss 69 of a housing 70 with one end of the countershaft 68 being arranged with a bevelled gear 71 meshing with a bevelled pinion 72 fixedly mounted on the shaft 30. In the present instance the disk 67 is arranged with two rollers 65, so that one revolution of the disk 67 will impart two intermittent movements to the turret 44 and position the horns 38 to two succeeding stations. The housing 70 is supported from the underface of the table T and is arranged with one of the bearings 45 for the turret 44. The housing 70 is adapted to enclose the wheel 61 and disk 67 to prevent the accumulation of foreign matter about the same. Two of the bearing hangers 31 are supported by the housing 70, as shown in Figure 11.

The initial station a of each of the horns 38 is relative to means for engaging a flange or head 40 i of a spool on the reduced end 59 of the horns in abutting relation with the stripper sleeve 73. The flanges used in the apparatus are of annular shape formed from sheet metal having the outer peripheral edge beaded or curled, as at 45 j in Figure 17, and the peripheral portion of the central opening extended in the direction and of a length substantially the depth of the bead, as at k, so that an annular recess is formed in one face of the flange. It is to be understood that the flange may be of any shape, such as circular, square, hexahedral or octagonal. The flange engaging means is carried by a bifurcated bracket or standard 78 having lateral flanges secured to a side edge of the table T intermediate the ends 55 thereof, as at 77, and a platform 78 supported at the opposite ends by the side walls of the bifurcated bracket to extend transversely of the bracket and constitute the supporting bottom of a hopper for the flanges comprising an annular 60 base member 79 supported by the opposite side walls of the bracket 78 with the lower end thereof spaced from the platform 78 a distance slightly greater than the thickness of a flange i. The diameter of the base member 79 is slightly greater 65 than the diameter of the flange i to retain said flanges in stack formation with the lowermost flange being supported by the platform 78, and to decrease the cost of construction, the base member 79 may be rather narrow or short and 70 a series of posts 80 are mounted in the upper end of the base member to maintain the flanges in stack formation to any desirable height.

To position and support the lowermost flange of the stack of flanges on edge in horizontal alignment 75

ment with the horn 33 positioned at said initial station α , there is provided a support in the form of a pocket in the face of the bracket 76 extending parallelly of the axis of the rotation of the
5 turret 44 and in opposed relation to the horn 33 comprising a rectangular recess or channel 81 in said face and a corresponding plate 82 fixed at the opposite longitudinal edge portions to the face adjacent the marginal edges of the recess
10 (Figure 20) and arranged with an elongated opening having a rectangular portion 83 at the upper end thereof and a circular portion 84 at the lower end in alignment with the horn 33 at said station. To maintain the flange in a vertical
15 plane in registry with the circular portion 84 of the opening in plate 82, a pair of jaws 85 are slidably mounted in opposed recesses in the plate 82 at diametrically opposite portions of the circular opening 84 with the gripping faces of the
20 jaws of arcuate form corresponding to the curvature of the flange and yieldingly urged toward each other into gripping engagement with the bead β of the flange in the pocket by flat springs 86 fixed at one end on the side edges of the plate
25 82 with the free ends engaging the jaws.
The lowermost flange of the stack of flanges is transferred from the hopper to the flange supporting pocket by a slide 87 having a cut out portion at one end with the marginal edges undercut, as indicated at 88 in Figure 21, to engage the lowermost flange being supported on the platform 73 and separate said flange from the flange above said engaged flange. The slide is
30 slideable in slideways 89 arranged in the opposite side walls of the bracket 76 and reciprocated toward and away from the hopper by a slide block 90 arranged with a recess in the upper face thereof to receive the rear end of the slide 87, as shown at 91 in Figure 12. The slide block 90 is slideable
35 in slideways 92 below the slideways 89 in the opposite side walls of the bracket 76 and actuated from the longitudinal shaft 30 through a lever 93 pivotally mounted in the lower portion of the bracket 76, as at 94, with the free end of the
40 upper arm of the lever bifurcated to engage a transverse pin in an arcuate recess in the slide block, as at 95. The free end of the lower arm of the lever is bifurcated for the pivotal mounting of a collar 96 having adjustably secured thereto
45 one end of a connecting rod 97 having an elongated strap 98 connected to the opposite end of the rod and encircling the shaft 30 adjacent a cam disk 99 fixedly mounted on the shaft 30 and adapted to engage rollers 100 rotatably carried
50 by the diametrically opposite end portions of the strap. The slide 87 is connected to the slide block 90 to impart retrograde movement of the block to the slide by a latch 101 pivoted at one end on the upper face of the slide 87 with the
55 free end of hook formation to engage the rear end of the slide block 90, as at 102 in Figures 12 and 21. The hook end 102 of the latch 101 is normally positioned out of engagement with the slide block 90, for a purpose to be hereinafter
60 disclosed, by a slide 103 slidably mounted in a slideway formed by a plate 104 in conjunction with a recess in the exterior of a side wall of the bracket 76, to engage an arm 105 fixed to and extending laterally from the latch 101 under the
65 influence of a spring 106 anchored at one end on the exterior of the side wall of the bracket 76 with the opposite end attached to an angle portion of a triangular plate 107 pivotally mounted at another angle portion thereof on the bracket
70 76 whereby the remaining angle portion of the

plate will engage a projection 108 extending laterally from the slide 87 and normally position the hook end 102 of the latch 101 out of engagement with the slide block 90 under the influence of the spring 106. The forward movement of the slide 87 will move the lowermost flange along the platform 78 past the forward end thereof which is beveled, as at 109, to tilt and direct the flange under the force of gravity to slide down a sloping portion 110 of the face of the bracket 76 into the portion of the pocket in said face arranged with the circular opening 84, as shown in Figure 12.

The flange positioned in the supporting pocket 81 of the bracket 76 in alignment with the circular opening 84 of the plate 82 is engaged on the reduced end 59 of the horn 38 positioned at said station *a* by a hollow plunger 111 slidably mounted in a tubular portion 112 integral with and extending laterally from the rear of the face 20 of bracket 76. Said plunger is reciprocated in the tubular portion by the lever 93 by being adjustably connected to the upper arm of lever 93 by a screw threaded link 113 screw threaded in a socket portion 114 at the rear end of the 25 plunger with the link being maintained in adjusted position in said socket by a lock nut 115 and the free end of the link arranged with a bifurcation 116 straddling the lever 93 and adjustably connected thereto through a pin and 30 slot connection 117 which is maintained in adjusted position by a set screw engaged in a boss of the slot in the lever, as shown at 118 in Figure 12. By this arrangement of parts a flange is positioned on the horn 38 by the plunger 111 simultaneously to the feeding of a flange from the hopper 79 by the slide 87, said latter flange being maintained on the sloping portion 110 of the face of the bracket 76 by the plunger 111 in its advanced flange-engaging position, as shown in 35 Figure 12, and will drop into the pocket of the bracket 76 when the plunger is in its rearward position to be positioned by the plunger in the succeeding forward movement thereof onto the succeeding horn. To prevent the withdrawing of 40 a flange positioned on a horn from said horn by the retrograde movement of the plunger 111, means to engage and maintain said flange on the horn is provided comprising a head 119 slidably mounted on a rod 120 fixed at one end 50 in the end of the bore of the plunger 111 to extend centrally thereof and terminating adjacent to the outer end of the plunger with an enlarged end thereof engaged in a recess in the outer end of the head 119, as at 121 in Figure 55 12, so that the outward movement of the head 119 is limited. Said head is normally positioned to extend from the outer end of the plunger by a spring 122 coiled about the rod between the end of the bore of the plunger and the head. 60 The head 119 moves with the plunger 111 and during the forward movement of the plunger in engaging a flange on a horn, the head will engage the end of the horn and compress the spring 122 permitting the plunger to continue its forward movement and engage the flange on the horn. During the retrograde movement of the plunger, the head 119 will be maintained in engagement with the horn under the influence of the spring 122 and strip the flange from the 70 longer, and in the rearward position of the plunger will be positioned within the tubular portion 112 out of the pocket 81 by the enlarged end of the rod 119.

The flanges i are supported in the hopper 79 75

with the recessed faces formed by the bead *j* and the central extended portion *k* uppermost so that the flanges will be positioned in the supporting pocket *81* with said recessed face opposite the horn and be engaged on the horn with the recessed face in opposed relation to the annular member *73* of the stripper mechanism of the horns, as shown in Figure 12.

After a flange *i* is positioned on a horn, the turret is actuated to position said horn at station *b* where no operation takes place.

At station *c*, a tubular core *l* is positioned on the reduced end *59* of the horn *38* with the forward end portion of the core in engagement with the central extension *k* of the flange *i* and said forward end of the core projecting from the extension *k* into the die recess *69* of the horn. The cores *l* may be supplied to the apparatus from a suitable hopper or directly from apparatus for making said cores. Core making apparatus of the type embodied in my pending application Serial No. 77,589 filed May 2, 1936, may be utilized in conjunction with the present apparatus, and in which core making apparatus, the cores are formed from a flat sheet of metal about a mandrel *123* (Figures 1, 2, 3 and 4) extending from said core making apparatus to the apparatus of the present application and terminating in a tubular holder or support for the cores. The tubular holder for the cores comprises a pair of semi-circular members *124*, *125*, member *124* being fixedly mounted on the table *T* by a longitudinal bracket *126* supported at one end on the table opposite the end arranged with the crank shaft *22* and having vertical supports *127* with the upper ends arranged to engage and support the holder member *124*. The core supporting member *125* is movably mounted to have movement toward and away from the member *124* and permit an inspection and removal of cores therefrom by arranging the member *125* with a vertical rib *128* adapted to be engaged in recesses arranged in arms *129* and releasably retained in said recesses by screws, as at *130* in Figure 5, with the arms *129* slidably mounted on posts *131* fixed in and extending perpendicularly from one side of the bracket *126*. The arms *129* are maintained in adjusted position on the posts *131* by set screws *132* threaded in the arms to engage the posts, whereby the member *125* may be positioned various distances from the member *124* to provide longitudinal slots *154* on the opposite sides of the holder, and as shown in dotted lines in Figure 5, to permit inspection and removal of cores, and also for the purpose of accommodating cores of different diameters.

The cores are transferred from the mandrel *123* to the support *124*, *125* and intermittently moved along said support by a series of fingers *133* pivotally mounted on pins *134* fixed in and extending perpendicularly from equidistantly spaced supports *135* integral with and extended from opposite side portions of a slide *136* slidably supported in a slideway formed in a longitudinal channel portion *137* of the bracket *126* with gibs *138* fixed on the opposite side walls of the channel to extend over the slide *136*, as clearly shown in Figure 5. The slide *136* is reciprocated toward and away from the mandrel *123* and the horn positioned at station *c* by the rotation of the shaft *30* through a crank mechanism comprising a collar *139* fixedly engaged on the end of the shaft *30* extending from a hanger *31* and having a pin *140* fixed in and extending longitudinally therefrom and rotatably engaged by a boss of a

socket member *141* having screw threaded thereto one end of a rod *142* having the opposite end adjustably carrying a sleeve *143* pivotally connected to an arm *144* rotatably mounted on a stud shaft *145* fixedly supported in a boss *146* mounted on the end of the table *T*. The arm *144* is arranged to carry a bevelled gear *147* meshing with a bevelled gear *148* fixedly mounted on the end of a shaft *149* rotatably mounted in bifurcated portions *150* of the bracket *126*. The reciprocation of the shaft *149* by the movement of the crank rod *142* will reciprocate an arm *151* fixedly mounted on the shaft *149* and pivotally connected to the slide *136* through a pin and slot connection *152*. The channel portion *137* of the bracket *126* is arranged with an elongated opening *153* to permit reciprocation of the pin and slot connection *152*, and the supports *135* of the slide *136* are positioned on opposite sides of the supports *127* for the core supporting member *124* to position the fingers *133* in alignment with the opposite slots *154* in the core support *124*, *125*. The free ends of the fingers *133* are yieldingly urged to extend through said opposite slots *154* to engage the rear end edges of the cores on the mandrel *123* and in the support *124*, *125*, by leaf springs *155* fixed at one end in the pivot pins *134* with the free ends engaging pins *156* fixed in and projecting from the fingers *133* intermediate the pivot pins *134* and the free end of the fingers *133*. The free ends of the fingers are positioned in the core support *124*, *125* and recesses *157* on opposite sides of the mandrel *123* by ears *158* integral with and extending rearwardly from the pivoted ends of the fingers to engage stop pins *159* fixed in and extending perpendicularly from the fingers supports *135*. The slide *136* in its rearward position will position the last pair of fingers *133* to engage the rear edge of a core on the mandrel *123* which core has been positioned adjacent the end of the mandrel within the core support *124*, *125* by the feeding mechanism of the core forming apparatus, not shown, so that the forward movement of the slide will transfer said core from the mandrel to the core support *124*, *125*, and the first pair of fingers will transfer a core from the core support *124*, *125* to the reduced end *59* of the horn positioned at station *c*. The forward end of the core will readily engage the central opening of the flange *i* on the reduced end *59* of the horn *38* positioned at station *c* as the flange about said opening therein extends in an arcuate direction to the extending portion *k* thereof.

During the retrograde movement of the slide *136* the fingers *133* are moved out of the opposite slots *154* of the core holder *124*, *125* against the force of the springs *155* by engaging the cores in the holder *124*, *125*, and to prevent the cores being moved from their advanced positions, the cores are retained in their advanced position by detents *160* carried at one end of resilient members *161* fixed at the other ends to the bottom of the core supporting member *124* to normally position the detents into openings in the member *124*. The forward face of the detents is angularly recessed to engage the rear edge of the advanced cores, as shown in Figure 11, and the rearward face thereof of arcuate shape to permit the advancing cores to ride over and move the detents through the openings in the member *124* against the force of the resilient members and out of the path of movement of the advancing cores.

To prevent the flange *i* being expelled from the reduced ends *59* of the horns *38* by centrifugal force through the rotation of the turret *44* in po-

sitioning the horns at stations *b* and *c*, there is provided a pair of guide rails 162 extending in an arcuate direction from the flange supporting pocket 81 in the bracket 76 to a point past the core supporting members 124, 125, above and below the reduced horn end 59, and supported by brackets 163 mounted on the face of the bracket 76 and on a side wall of the channel 137 of the bracket 125, as shown in Figures 1, 2 and 7.

10 After a core *l* is engaged on the reduced end 59 of the horn 38 in engagement with a flange *i* thereon, said horn is advanced to station *d* where no operation is performed, and from station *d* the horn is moved to station *e* where a second 15 flange *i'* is engaged on the outer end of the core with said outer end of the core projecting from the extension *k'* of the central opening of the flange *i'*. The means for engaging the flanges *i'* on the cores are of identical structure as the 20 means for engaging the flanges *i* on the reduced ends of the horns, and therefore, a description of the same is believed to be unnecessary and like characters will designate like parts in both means for engaging flanges *i* and *i'* on the horns. The 25 plunger 111 of the means for engaging the flange *i'* on the outer end of the core is not arranged with the slideable stripper head 119 but has a head 164 (Figure 13) fixedly mounted in the bore of the plunger with an annular enlarged portion intermediate the ends of the head abutting a shoulder formed in the bore of the plunger, as at 165. The outer end of the head has a section flaring from the intermediate enlarged portion thereof, as at 166, to engage and flare the 30 end portion of the core projecting from the flange *k'* after said flange *i'* is engaged on the core, as shown at *m* in Figures 13 and 17. The head 164 is secured in the bore of the plunger 111 by a screw 167 engaged in the head and screw threaded in the plunger with the head of the screw counter-sunk in the head 164, as shown in dotted lines at 168 in Figure 13.

To prevent the waste of the flanges *i* and *i'* when there has been no core engaged on the 45 reduced end 59 of the horn 38 by the first pair of fingers 133, the latches 101 of both means for feeding the flanges *i* and *i'* are normally positioned out of engagement with the slide blocks 90 to prevent the actuation of the slides 87 and the feeding of the flanges to the flange supporting 50 pockets 81, as hereinbefore described. The latches are maintained in their normal inoperative positions if cores are absent at predetermined points in the core supporting members 124, 125, and if cores are at said points, the latches are actuated to engage and connect the slide blocks 90 with the slides 87 against the tension of the springs 106. This purpose is accomplished in conjunction with the means for feeding the 55 flanges *i* by a shaft 169 rotatably mounted in bearings of brackets 170 supported on the table T on one side of the bracket 76 of said feeding means with one end of the shaft terminating adjacent said bracket 76 and carrying an arm 171 having a set screw 172 adjustably mounted in the free end of the arm to engage the projection 108 of the slide 103 of said feeding means, as shown in Figures 1 and 2. The opposite end of the shaft 169 carries another arm 173 having at the free end thereof a link connection 174 with an intermediate portion of a pair of levers 175 pivotally mounted at one end on opposite sides of one of the brackets 170 with the other end of said levers arranged with a shoe in the form 60 of a plate 176 having a recess in the upper edge

thereof to engage the lower edge and outer sides of the levers 175, as shown at 177 in Figures 3 to 5, inclusive. The shoe plate 176 is adjustably mounted on the levers 175 to have movement longitudinally of said levers by a clamping plate 178 engaged over the upper edges of the levers 175 and a screw 179 engaged in the plate to extend between the levers and screw threaded in the shoe plate. The lower end of the shoe plate 176 is adjustably positioned by an abutment member 180 screw threaded in a vertically extended portion 181 of a side wall of the channel portion 137 with the head of the abutment adapted to engage the lower edge of the levers 175, as shown in Figure 5, so that the lower 15 end of the shoe plate will be engaged by an actuator plate 182 pivotally mounted on the pivot pin 134 of the right hand finger 133 of the last pair of fingers, looking at Figures 3 to 5, inclusive, the actuator plate 182 having a lateral extension 183 at the outer side edge thereof with the opposite inner side edge yieldingly positioned to extend into the right hand recess 157 of the mandrel 123 and through the right hand slot 154 of the core supporting members 124, 125 to engage a core being transferred from the mandrel 123 to the core support 124, 125 and which will be positioned on the reduced end 59 of the horn 38 which is positioned at station *g* when said core is in position to engage the inner edge of 30 the actuator plate 182 and position the actuator plate extension 183 in engagement with the shoe plate 176, thereby lifting said shoe plate and the free ends of the levers 175 and arm 173, rotating the shaft 169 in a clockwise direction, actuating the set screw 172 into engagement with the projection 108 and depressing the slide 103 against the force of spring 106 which will permit the latch 101 under the force of gravity to engage the slide block 90 and the feeding of the lowermost flange *i* from the hopper 79 by the slide 87 to the pocket 81 to be engaged by the plunger 111 on the horn which is positioned at station *g* when the slide 87 is connected to the slide block 90. The inner side edge of the actuator plate 182 is yieldingly urged into the slot 154 by a leaf spring 184 fixed at one end in the pivot pin 134 of the plate 182 with the free end thereof engaging a pin 185 fixed in and extending perpendicularly from the plate 182 adjacent the outer side edge thereof. To facilitate the engaging and lifting of the shoe plate 176 by the actuator plate 182 the forward end edge of the actuator plate is bevelled, as at 186, and the side edge of the shoe plate 176 adjacent the bevelled end 186 of the actuator plate is cut away and bevelled, as at 187 in Figures 1 and 3. The core feeding finger 133 which is mounted on the pivot pin 134 on which the actuator plate 182 is mounted, is of approximately half the thickness as the other fingers 133, 60 and the actuator plate 182 is of similar thickness to permit both of said finger and plate to enter the slot 154 of the core supporting members 124, 125. Should there be no core on the mandrel 123 to be transferred to the core support 124, 125, the lateral extension 183 of the actuator plate 182 will be positioned by the spring 184 out of engagement with the shoe plate 176 and the latch 101 will be maintained out of engagement with the slide block 90 by the spring 106 and no flange 70 *i* will be fed and positioned on the designated horn at station *g*.

Should there be no core in supporting members 124, 125 to be engaged by the first pair of feeding fingers 133 and be positioned on the 75

horn at station *c*, the feeding means for the flanges *i'* will be rendered or remain inoperative so that no flange *i'* will be engaged on the horn that has no core engaged thereon, by mechanism 5 which is identical in structure and operation with the mechanism for actuating the latch 101 into engagement with the slide block 90 of the means for feeding the flanges *i* to the horns at station *a* except that the shaft 169 of the mechanism for controlling the feeding of the flanges *i'* does not extend beyond the end of the table *T* as the shoe plate 176 is positioned relative to the left hand finger of the first pair of fingers 133, as clearly shown in Figures 1, 2, 3 and 5, and 10 therefore, like characters will designate like parts in both mechanism for actuating the latches 101.

The outer end of the core engaged on the horn positioned at station *d*, will be engaged by a 20 flange *i'* which is supported on the sloping portion 110 of the face of the bracket 75 mounted on the left hand side of the table *T*, as shown in Figure 12.

After the second flange *i'* has been engaged 25 on the free end of the core *l*, the horn at station *e* is actuated to station *f* where no operation is performed and then said horn is positioned at station *g* where the opposite end portions of the core *l* are curled or crimped with 30 the central extensions *k*, *k'* of the flanges *i*, *i'*, respectively, to form a complete spool with the flanges secured to the core. During the travel of the horn from station *e* to station *g* the second flange *i'* is retained on the core by flared end 35 *m* of the core.

The opposite ends of the core are curled or crimped with the central extension of the flanges by the die 60 arranged in the face of each of the horn bodies 38 and a reciprocating die at station 40 *g* comprising a head 188 having a face arranged with a reduced portion 189 and an annular recess or groove 190 extending about the reduced portion to form a die portion corresponding to the die 60 with a protuberance 191 extending 45 centrally from the reduced portion 189 to engage a corresponding recess 192 in the reduced portion 55 59 of the horns 38 (Figure 15) during the crimping operation to aline the horns 38 at station *g* with the reciprocating die. The head 188 is arranged 50 with a shank portion 193 extending from the rear thereof to engage and mount the head in a socket member 194 releasably mounted in a recess of a cross head 195 secured to a slide 55 196 slidably mounted in a slideway formed on the table *T* between the legs of the yoke shaped bracket 23 by blocks 197 adjustably mounted on the legs of the bracket to have movement toward and away from each other by set screws 198 and gibs 199 secured to the slideway blocks 60 197. The slide is reciprocated by the crank shaft 22 through a connecting rod 200 having screw threaded end portions with one end portion adjustably engaged in a longitudinally split tubular portion 201 of a split collar member 202 65 engaged on a crank pin 203 of the crank shaft with the engagement between the rod and the split tubular portion being secured by clamping the tubular portion to the rod through a clamping screw 204. The other screw threaded end 70 portion of the rod 200 is adjustably engaged in a longitudinally split tubular portion 205 of a collar member 205 engaged on a pin 207 mounted at the end and extending between the walls of a bifurcation 208 at the rear end of the slide 75 196 with the rod retained in adjusted position

in the tubular portion 205 by a clamping screw 209 engaged in the split collar portion 205. The intermediate portion of the connecting rod 200 is arranged for the application of an implement to rotate the same, such as a wrench, and as shown 5 is arranged for the application of a pin wrench. By the forward movement of the slide 196 toward the horn positioned at station *g*, the die groove 190 will engage the flaring end *m* of the core *l* and primarily curl said end with the central extension *k'* of the flange *i'*, as shown at *n* in Figure 18, and simultaneously engage the opposite end of the core and the central extension *k* of the flange *i* against the die groove 60 of the horn and primarily curl said opposite end of the core with the flange extension *k*. The extreme forward movement of the slide 196 will finally curl both ends of the core with the extensions *k* and *k'*, as shown at *o* in Figure 19, whereby the core *l* is securely connected to the flanges *i* 20 and *i'*. To prevent the formed spool being withdrawn from the horn by the retrograde movement of the die head 188, stripper mechanism similar to the stripper mechanism 73 of the horn is provided, comprising an annular member 210 25 slidably mounted on the die head 188 to have limited movement by headed pins 211 fixed in the socket member 194 and engaging openings in the annular member and said member is yieldingly urged against the spool flange *i'* to strip the 30 spool core from the reduced portion 189 of the die head by springs having the opposite ends engaged in recesses in the annular member 210 and socket member 194, as at 212 in Figure 11.

To prevent the crimping action of the reciprocating die head 188 from collapsing the core and maintain the spool flanges at a predetermined distance from each other, clamping means are provided to engage the spool core prior to the crimping of the spool core with the extensions 40 *k*, *k'* of the flanges *i*, *i'*, comprising a pair of jaws 45 in the form of plates 213 having one end arranged with an arcuate recess 214 to engage opposite upper and lower portions of the core and the opposite ends of said jaw plates arranged with a transverse head 215 slidably mounted in a slideway 216 of greater length than the length of the transverse heads. Said slideway 216 is arranged 50 in carriers 217, 218 slidably mounted in channel members 219 having flanges fixed to cross members 220, 221 by clamping plates, as at 222, with said cross members having bosses 223 at the opposite ends engaged on tubular members 224 55 mounted in tubular portions 225 integral with and extending below the table *T* with an annular flange of each tubular member 224 engaging the upper face of the table to support the tubular members 224 on the table, as at 226. The cross member 220 is supported on the tubular members in spaced relation to the cross member 221 and 60 above the axes of the reciprocating die 188 and the horns 38 by sleeves 227 engaged on the tubular members 224 with the ends abutting the bosses 223 of the cross members 220, 221. The bosses 223 of the cross member 221 have recessed portions to engage the annular flanges 226 of the tubular members and permit the supporting of said bosses by the table *T*, as clearly shown in Figure 14. The carrier 217 is associated with the cross member 220 and is adjustably supported in 65 the channel member 219 by a thumb screw 228 screw threaded at one end in a screw threaded bore 229 in the carrier 217 and having a reduced portion 230 engaged in a recess 231 midway of the ends of a plate 232 fixedly engaged at said ends 70 75

on rods 233 having shoulders 234 to engage and support the plate, and said rods being slidably mounted in the tubular members 224. The screw 226 is adapted to be adjusted by rotating the 5 same in the plate 232 through the thumb head thereof and is retained in adjusted position in the carrier member 217 by a lock nut engaged on the screw in abutting relation to the carrier, as shown at 235 in Figure 14. The rods 233 are secured to 10 the plate 232 by washers and nuts engaged on the ends of the rods projecting above the plate 232 with the shoulders 234 abutting the lower face of the plate, as at 236. The carrier 218 is associated with the cross member 221 and is slidably supported in the channel member 219 of said cross member 221 by a thumb screw 237 screw threaded at one end in a screw threaded bore 238 in the carrier 218 and having a reduced portion 239 adjacent the head of the screw engaged in a recess 240 midway of the bifurcated ends of a connecting member 241 connected to the rods 233 through toggle connections comprising pairs of links 242 pivotally mounted intermediate their ends on a pair of sleeves 243 engaged on the 15 tubular members 224 with one end of said links pivoted in the bifurcated ends of the connecting member 241 and the opposite ends thereof pivotally connected to one end of pairs of links 244 pivotally connected at the opposite ends to the 20 projecting ends of a cross member 245. The lower ends of the rods 233 are fixed to the cross member 245, as by nuts 246 engaged on the rods to abut the opposite faces of said cross member. The rods 233 are reciprocated and the jaws 214 25 are actuated toward and away from each other through the toggle connections 242, 244 by a cam disk 247 fixedly carried by the shaft 30 and a roller 248 rotatably mounted in an arcuate recess in the cross member 245 and yieldingly urged in a direction to engage the cam by springs 249 connected at one end to the end projections of the cross member 245 and the opposite ends anchored to the base B by eye bolts 250 engaged in the base. The springs will also urge the jaws 214 30 toward each other and the upper and lower peripheral portions of the core on the reduced end 59 of the horn 38 positioned at station g. The cross member 222 and the sleeves 243 are retained on the tubular members 224 by nuts 251 engaged on the opposite ends of the tubular members 224 in abutting relation with the cross member and sleeves, said nuts being arranged for the application of a pin wrench, as shown in Figures 11 and 14. It will readily be seen by the 35 disclosure of Figure 14 that the upward movement of the rods 233 by the high portion of the cam disk 247 engaging the roller 248 will actuate the carrier 217 and the jaw 214 carried thereby in an upward direction away from the core on the horn 38 at station g and actuate the carrier 218 and the jaw 214 carried thereby in a downward direction away from the core on the horn 38 at station g by moving the connected portions of the links 242, 244 in an upward direction, as 40 shown in full lines, and the downward movement of the rods 233 under the force of the springs 249 will move the jaw carrier 217 in a downward direction toward the core on the horn at station g and actuate the jaw carrier 218 in an upward direction toward the lower portion of the core on the horn by moving the connection between the links 242, 244 in a downward direction, as shown in dotted lines. The cam disk 247 is arranged and actuated so that the high portion thereof 45 will engage the roller 248 when the reciprocating 50

die 190 is spaced from the outer end of the core and the extension k' of the flange i', the inoperative positions of the jaws 214 and the die head 183 being shown in Figure 15.

To permit the longitudinal movement of the core during the forward crimping movement of the reciprocating die head 188 and the crimping of the inner end of the core and the central extension k of the flange i by the fixed die 66 of the horn 38, the jaw plates 213 will move with 5 said core in the slideway 216 of the carriers 217, 218 against the force of coil springs 252 having one end abutting an end wall of the slideway and the opposite ends engaged in an elongated recess in one end of the transverse head 215, as 10 shown in Figures 11 and 15. The jaws 214 are normally positioned centrally of the core on the horn at station g by set screws 253 engaged in the opposite end wall of the slideway 216 to abut the opposite end of the head 215 to position the jaws 15 centrally of the core against the tension of the springs 252, as shown in Figure 15.

To prevent the jaw plates 213 ejecting the flange i' from the core on the horn 38 when said plates are actuated toward and engage the core, 20 there is provided a plate 254 mounted at the ends on the sleeves 227 and having an elongated opening 255 intermediate the ends to permit movement of the die head 188 toward the horn and of such a width that the marginal side portions of the 25 plate will engage the flange i', as shown in Figures 30 11 and 14.

After the flanges have been secured to the core and the spool has been formed, the horn carrying the formed spool is positioned at station 35 h when the formed spool is ejected from the horn. If it is desirable to form a tongue t from the material of the core l to extend inwardly from the core for anchoring the web to be wound upon the spool core to said core, the formed spool is 40 transferred from the horn at station h to a horn of another series of horns 256 equidistantly spaced about the periphery of a head 257 of a second turret 258 rotatably mounted in a bearing boss 259 extending from the lower face of the 45 table T. There are three horns 256, in the present instance, having an annular shoulder 260 adjacent one end with said end engaged in recesses in the turret head 257, as at 261, and retained in 50 said recesses with the shoulders abutting the head by set screws 262, as shown in Figure 14. The upper portion of the horns 256 extending from the turret head is arranged with a longitudinal slot 263 for a purpose to be hereinafter described. The turret 258 is intermittently rotated in a 55 clockwise direction, as indicated by the arrow in Figure 2, to successively position the horns 256 in alignment with the horns 38 positioned at station h by the first turret 44, from said first turret through a gear 264 secured to the turret 44 by a 60 clamping plate and bolt engaged in the plate and turret, as at 265 in Figures 11 and 12. The gear 264 meshes with a pinion 266 rotatably mounted on a stud carried by the underface of the table T, as at 267 in Figure 1, to mesh with a gear 268 65 fixed to the end of the turret 258 extending from the bearing boss 259.

The formed spools are transferred from the horns 38 at station h to the horns 256 of the second turret 258 by reciprocating means actuated 70 during the interim in the actuation of the turrets 44, 258, comprising an angular member 269 adjustably mounted on a slide 270 by bolts 271 engaged in the slide and a slot 272 in one angle portion of the member 269. The slide 270 is slid- 75

angle brackets 313 and leading to a depository, not shown.

To facilitate the ejection of the spool from the horn 256, the spool is moved longitudinally on the horn in a direction away from the shoulder 260, as shown in Figure 9, by a cam face 310 arranged on the free end of an angle portion of an angular member 311 fixedly mounted on the table by the other angle portion thereof with the cam face positioned so that the outer face of the spool flange *i*' will first engage the pointed end of the cam face during the movement of the horn 256 from the punch 285 to the ejector arm 303. The cam face is arranged so that the spool will be gradually moved longitudinally of the horn and the tongue *t* formed by the punch 285 will be loosened from the slot 263.

Should there be no core in the supporting member 124, 125 at the leftmost actuator plate 182 (Fig. 2) for the latch 101 of the means 81, 93 for feeding the flanges *i*, the synchronized operation of the apparatus is as follows: After the upper arm of lever 93 at station *a* moves toward the turret 44 to actuate the plunger 111 to engage a flange *i* on the horn 59 at said station and actuate the slide 87 to feed a flange *i* onto the sloping face 110, the absence of a core at said leftmost actuator plate 182 renders said latch 101 inoperative. Then the upper arm of lever 93 moves away from the turret, but the slide 87 remains inoperative. Upon the movement of the upper arm of lever 93 from the turret, the plunger 111 is also moved away from the support 81, 82 whereupon the flange *i* on the sloping portion 110 will drop into the support 81, 82. Then the slide 136 operates, but no core is present at the leftmost actuator plate 182 and consequently no core is transferred by the fourth pair of feeding fingers 133, looking at Figure 2. During the movement of the upper arm of lever 93 from the turret, the turret 44 rotates and horn 59 with a flange *i* is moved from station *a* to station *b*. The upper arm of lever 93 moves toward the turret to actuate the plunger 111 and engage the flange *i* in the support 81, 92 onto the horn positioned at station *a*, but no flange is fed to the sloping portion 110. Then the upper arm of lever 93 moves from the turret and the turret rotates to position the horns having flanges *i* thereon to stations *c* and *b* from stations *b* and *a*, respectively. The last movement of the upper arm of lever 93 from the turret may or may not move the slide 87 therewith depending upon whether there is a core in the supporting members 124, 125 at the last actuator plate 182 to render the latch 101 operative but the further operation of the lever 93 will be a repetition of the operation thereof hereinbefore described. The slide 136 will actuate the first pair of fingers 133 to engage and move the core *l* in the members 124, 125 at the first actuator plate 182 for the latch 101 of the means 81, 93 for feeding the cores *i*' at station *c*, onto the horn at station *c* having the flange *i* thereon and will actuate the second pair of fingers 133 to move a core *l* relative to the first actuator plate 182, and the third pair of fingers 133 will not move any core *l*. Then the turret will move the horn having the flange *i* and core *l* thereon from station *c* to station *d*, move the horn having the flange *i* thereon from station *b* to station *c*, and move the horn having no flange thereon from station *a* to station *b*. The slide 136 will actuate the first pair of fingers 133 to position a core *l* in the members 124, 125 at the first actuator plate 182 upon the horn having the flange *i* thereon at station *c* and the second pair of fingers 133 will not move any core *l*. Then the turret 44 will rotate and move the horn having the flange *i* and core *l* from station *d* to station *e*, move the horn having the flange *i* and core *l* from station *c* to station *d*, and move the horn having no flange *i* thereon from station *b* to station *c*. The slide 136 operates but no core is present in the members 124, 125 at the first actuator plate 182 and no core *l* will be engaged on the horn having no flange *i* at station *c*. Then the upper arm of lever 93 connected to the slide block 90 and plunger 111 at station *e* moves toward the turret 44 to position a flange *i*' on the core *l* positioned on the horn at station *e*. Then the upper arm of lever 93 connected to the slide block 90 and plunger 111 at station *e* moves from the turret to remove plunger 111 from the support 81, 82 whereby flange *i*' on the sloping portion 110 will drop into the support 81, 82, and the slide 87 remains inoperative due to the rendering of the latch 101 inoperative by the absence of a core *l* in the members 124, 125 at the first actuator plate 182. Then the turret 44 is rotated to move the horn having the core *l* and the flanges *i*, *i*' at the opposite ends thereon from station *e* to station *f*, move the horn having the core *l* and flange *i* at the inner end thereof from station *d* to station *e*, and move the horn without the core *l* or flange *i* thereon from station *c* to station *d*. The upper arm of lever 93 moves toward the turret and actuates the plunger 111 to position the flange *i*' in the support 81, 82 onto the core on the horn at station *e*, but no flange *i*' is fed to the sloping portion 110. The slide 136 will actuate the first pair of fingers 133 to engage a core on the horn at station *c* if said horn has received a flange *i* at station *a*. Then the turret 44 rotates and the horn at station *f* is moved to station *g*, the horn at station *e* is moved to station *f*, and the horn without a core *l* or flange *i* is moved from station *d* to station *e*. The upper arm of lever 93 at station *e* moves toward the turret but no flange *i*' is positioned on the horn at station *e* by the plunger 111 and a flange *i*' may be positioned on the sloping portion 110 if the latch 101 is rendered operative by a core in the members 124, 125 at the first actuator plate 182 and there will be a repetition of the operation of the lever 93 as hereinbefore described. The slide 196 moves toward the turret 44 and actuates the die 188 to crimp the flaring end *m* of the core *l* with the extension *k*' of the flange *i*' and the opposite end of the core *l* with the extension *k* of the flange *i* to form a spool on the horn at station *g*. Then the turret rotates and moves the horn having a formed spool thereon from station *g* to station *h*, moves the horn at station *f* to station *g*, and moves the horn without the core *l* and flanges *i*, *i*' from station *e* to station *f*. The slide 196 moves toward the turret and forms the core *l* and flanges *i*, *i*' on the horn at station *g* into a spool. The angular member 269 moves from the horn 59 at station *h* to a horn 256 to transfer the formed spool from said horn 59 to horn 256. The slide 196 moves from the turret 44. The angular member 269 moves from the turret 258 to the turret 44. Then the turret 44 rotates to position the horn 59 having the formed spool removed therefrom at station *h* relative to station *a*, position the horn 59 having the formed spool thereon at station *g* to station *h*, and position the horn without the core *l* and flanges *i*, *i*' from station *f* to station *g*. The turret 258 rotates and moves the horn 256

ably supported in a slideway 273 mounted on the upper face of the table T and reciprocated in a direction parallelly of the axes of the horns 38, 256 at station h from the continuously rotating 5 counter shaft 68 through a cam disk 274 fixedly mounted on an end of a stud shaft 275 rotatably mounted in a bearing on the table T and adapted to be rotated from the countershaft 68 through gears fixed to said shafts, as at 276. The cam ext- 10 tends above the upper surface of the table T to engage a roller 277 carried by an arm 278 pivotally mounted at one end on the table T, as at 278', with the opposite end pivotally connected to one end of a link 279 having the other end pivotally 15 connected to an angle portion of a triangular member 280 pivotally mounted at another angle portion on the table T, as shown in Figures 2 and 7. The roller 277 is yieldingly urged to engage the cam disk 274 by a spring 281 anchored at one 20 end to the table T and the opposite end connected to the pivot connection between the arm 278 and link 279. The triangular member 280 is connected to the slide 270 to compensate for the rotary movement of the triangular member while im- 25 parting straight line reciprocatory movement to the slide through a slot 282 arranged in the free angle portion of the triangular member to engage a pin 283 fixed in and extended perpendicularly from the slide 270. The angle member 280 30 is arranged to engage a spool on the horn 38 at station h by spaced finger portions 284 extending laterally from the angle portion extending at a right angle from the angle portion arranged with the slot 272 of said member 269, as shown in Fig- 35 ure 10. The cam disk 274 is arranged to position the spaced fingers 284 to engage the spool on the horn 38 being actuated from station g to station h so that when the horn reaches station h the fingers 284 will be extending on opposite portions 40 of the core l and between the flanges i, i' of said spool, as shown in Figure 8. The fingers 284 having the spool engaged thereon are actuated from said position adjacent the horn 38 to a position adjacent the annular shoulder 260 of the horn 256 45 positioned in alignment with the horn 38 by the high portion of the cam plate 274 engaging the roller 277, whereby the spool is transferred from the reduced portion 59 of the horn 38 to the horn 256 and along said horn 256 to a position adjacent 50 the shoulder 260, as shown in Figures 2 and 7. At the termination of the forward transferring movement of the fingers 284, the turrets 64 and 258 are rotated so that the horn 38 at station h will be actuated past the slide 270 before the 55 fingers 284 reach their rearward position to engage the spool on the horn 38 at station g, and the horn 256 having the spool engaged thereon will be actuated in a direction away from the free ends of the fingers 284 to remove the transferred 60 spool from said fingers.

After the formed spool is removed from the fingers 284 it is positioned by the horn 256 at the next successive station thereof relative to means to form the web anchoring tongue t comprising 65 a punch 285 having a suitable cutting head at one end with the opposite end engaged in a split collar 286 having flanges at the opposite ends of the mating members of the collar to support the collar and punch in an elongated opening 287 of a laterally extending head of a slide 288 slidably mounted in a vertical slideway 289 supported on the table T. The punch is adjustable in the opening 287 to be positioned midway of the opposite end of the core of spools of various lengths and 70 secured in adjusted position by a nut 290 engaged 75

on the end of the punch extending from the upper end of the collar with a shoulder 291 on the punch abutting the lower end of the collar. The punch head co-operates with the longitudinal slot 263 of the horns 256 to form the web engaging 5 tongue t, the slot acting as the die for the punch, as shown in dotted lines in Figure 16. The slide 288 is actuated in synchronism with the actuation of the spool transferring fingers from the longitudinal shaft 30 through an arm 292 (Figure 10 14) pivotally mounted at one end in a bifurcated bracket 293 suspended from the table T with the free end of the arm pivotally connected to the lower portion of the slide 288 through a pair of links 294. The arm 292 is reciprocated in a vertical direction by the rotation of the shaft 30 through a connecting rod 295 pivotally connected at one end to an intermediate portion of the arm 292 and having the opposite end arranged in the form of a strap 296 encircling an eccentric disk 20 297 fixed to the shaft 30. To maintain the punch 285 in alignment with the slot 263 in the horn 256 positioned relative to said punch and limit the tongue forming movement of the punch so that the punch will not damage said horn during said movement, the lateral head of the slide 288 is extended and arranged to carry a pin 298 (Figures 1 and 2) extending from the underface of the lateral slide head to engage a circular recess of a series of such recesses 299 in the top of the turret 30 head 257 about the periphery thereof, there being three recesses in the present instance, located midway of the horns 256, as shown in Figure 7. The spool on the horn 256 positioned in vertical alignment with the tongue forming punch 285 is maintained in alignment with the punch by a resilient finger 300 fixedly carried by a collar 301 adjustably mounted on a post 302 supported in the upper surface of the table T. The free end of the finger 300 is of curved formation to permit 40 engagement of the same by the outer surface of the spool flange i during the movement of the horn to its position in vertical alignment with the tongue forming punch 285. The finger is positioned on the post 302 so that said finger will 45 yieldingly move the engaged spool on the horn 256 and engage the spool flange i' with the shoulder 260 of the horn, as shown in Figure 7.

After a tongue t has been formed in the core of a spool, said spool is ejected from its supporting 50 horn 256 at the next station of said horn by a reciprocating ejector arm in the form of a plate 303 having one end bifurcated, as at 304, with the ends of the bifurcation legs bevelled to facilitate the engagement of said legs with the outer 55 face of the spool flange i', as shown in Figure 7. The ejector plate 303 is mounted, so that the bifurcation legs will extend on the opposite upper and lower portions of the horn 256, by the end of said plate opposite to the bifurcated end being 60 secured to a sleeve 305 rotatably mounted on a post 306 fixed in the upper surface of the table T and retained on said post by a collar 307. The ejector arm is reciprocated in synchronism with the spool transferring member 269 by the triangular member 280 through a link 308 pivotally connected at one end on said member 280 adjacent the pivot thereof with the opposite end pivotally connected to an ear portion 309 fixed to and extending laterally from the sleeve 305, as 65 shown in Figures 2 and 7. The movement imparted to the plate 303 is sufficient to remove the spool from the horn and deposit the spool on a chute 312 mounted on the side of the table T by 70 75

having the formed spool into engagement with the resilient finger 300. The slide 196 moves toward the turret 44, but no operation is performed as the horn at station *g* is without a core *l* and flanges *i*, *i'*. The angular member 269 moves from the turret 44 to turret 258 to transfer the formed spool from the horn 59 at station *h* to another horn 256 on turret 258. The punch 285 moves toward the formed spool on horn 256 engaged by resilient finger 300 to form the tongue *t*. The angular member 269 moves from the turret 258 to turret 44. Then the turret 44 rotates to move the horn 59 having the formed spool removed therefrom from station *h* to station *a*, and move the horn 59 having no core *l* nor flanges *i*, *i'* from station *g* to station *h*. The punch 285 moves from the horn 256 positioned relative thereto. The turret 258 rotates to position the horn 256 carrying the formed spool having the tongue *t* formed in the core portion *l* from the resilient finger 300 relative to the ejector arm 303, and position the horn 256 having the formed spool deposited thereon by the angular member 269 relative to the resilient finger 300. The angular member 269 moves from the turret 44 to the turret 258, but no formed spool is transferred. The punch 285 moves toward the horn 256 having the formed spool in engagement with the resilient finger 300 to form the tongue *t*. The ejector arm 303 moves outwardly along the horn 256 having the formed spool arranged with the tongue *t* to remove said spool from the horn 256. The punch 285 moves from the horn 256 positioned relative thereto. The ejector arm 303 moves toward the turret head 257. Then the turret 258 rotates to move the horn 256 carrying the formed spool arranged with the tongue *t* from the resilient finger 300 to the ejector arm 303, and moves the horn 256 without a formed spool thereon from the angular member 269 to the resilient finger 300. The punch 285 moves toward the horn 256 without a formed spool and no operation is performed. The ejector arm 303 moves outwardly along the horn 256 carrying the formed spool arranged with the tongue *t* to remove said spool from the horn. The punch 285 moves from the horn 256 without a formed spool. The ejector arm 303 moves toward the turret head 257. Then the turret 258 rotates to move the horn 256 without a formed spool from the resilient finger 300 to ejector arm 303. The ejector arm moves from the turret head 257, but no formed spool is removed from the horn 256 positioned relative to said ejector arm.

While I have described and illustrated one embodiment of the invention it will be obvious that various modifications may be made in the construction and arrangement of the parts and that portions of the invention may be used without others and come within the scope of the invention.

Having thus described my invention, I claim:

1. In apparatus for making sheet metal spools, a rotatable support, means to position a flange on said support, means to engage an end portion of a core with the flange on the support, means to engage another flange on the opposite end portion of the core on the support, means to secure the flanges to the core and form a spool on the support, means to eject the formed spool from the support, and means to actuate the support to positions relative to the successive operating means.

2. In apparatus for making sheet metal spools, a rotatable support, means to position a flange on

said support, means to position a core on the support and engage an end portion of the core with the flange on the support, means to engage a second flange on the opposite end portion of the core on the support and subsequently flare outwardly said opposite end portion of the core extending from the second flange, means to secure the flanges to the core and form a spool on the support, means to eject the formed spool from the support, and means to actuate the support relative to the successive operating means. 5

3. In apparatus for making sheet metal spools, a rotatable support, means to position a flange on said support, means to position a core on the support and engage an end portion of the core with the flange on the support, means to engage another flange on the opposite end of the core on the support, means to secure the flanges to the core and form a spool, means to form an inwardly extending tongue in the core between the flanges, means to transfer the formed spool from the support to the tongue forming means, and means to actuate the support to positions relative to the successive operating and the spool transferring means. 20

4. In apparatus for making sheet metal spools, a rotatable support, means to engage a flange on said support, means to engage a core on the support with an end portion of the core in engagement with the flange on the support, means to engage a second flange on the opposite end portion of the core on the support, means to crimp portions of the flanges and the core with each other to form a spool, a second rotatable support for a formed spool, means to transfer the formed spool from the first to the second rotatable support, means to form an inwardly extending tongue in the core between the flanges of the formed spool on the second support, and means to actuate the first support to successive 40 positions relative to the flange and core engaging means, the crimping means and the transferring means and actuate the second support to successive positions relative to the transferring means and the tongue forming means. 45

5. In apparatus for making sheet metal spools, a rotatable support, means to engage a flange on said support, means to engage a core on the support with an end portion of the core in engagement with the flange on the support, means to engage a second flange on the opposite end portion of the core on the support, means to crimp portions of the flanges and core with each other to unite the flanges with the core and form a spool, a second rotatable support for a formed spool, means to transfer the formed spool from the first to the second rotatable support, means to form an inwardly extending tongue in the core between the flanges of the formed spool on the second support, means to eject from the second support a formed spool having a tongue in the core thereof, and means to actuate the first support to successive positions relative to the flange and core engaging means, the crimping means and the transferring means and actuate the second support to successive positions relative to the transferring means, the tongue forming means and the ejecting means. 55

6. In apparatus for making sheet metal spools, a rotatable turret carrying a series of supports 70 equidistantly spaced about and extended radially from the turret, means to intermittently rotate the turret to position the supports at successive stations, means to engage a flange on the supports at the initial station, means at a succeeding sta- 75

- tion to engage a core on the supports with the forward end of the core engaging the flange on the supports, means at a succeeding station to engage a second flange on the rearward end of the core on the supports, means at a further succeeding station to crimp the opposite ends of the core with the flanges to form a spool on the supports, and means at the last station to eject the formed spool from the supports.

5 7. In apparatus for making sheet metal spools, a rotatable turret, a series of supports adjustably mounted on the turret to extend radially therefrom at predetermined distances and equidistantly spaced from each other, means to intermittently rotate the turret to position the supports at successive stations, means at the initial station to engage a flange on the supports, means at a succeeding station to engage a core on the supports with the forward end of the core engaging the flange on the supports, means at a succeeding station to engage a second flange on the rearward end of the core on the supports, means at a further succeeding station to crimp the opposite ends of the core with the flanges to form 10 a spool, and means at the last station to eject the formed spool from the supports.

10 8. In apparatus for making sheet metal spools, a rotatable turret carrying a series of supports equidistantly spaced about and extended radially from the turret; means to successively engage a flange on each of the supports, engage a core on the supports with one end of the core engaging the flange on the supports, engage a second flange on the opposite end of the core on the supports and crimp end portions of the core with the flanges to form a spool; a second rotatable turret carrying a series of supports equidistantly spaced about and extended radially from said second turret; means to transfer the 15 formed spools from the supports of the first turret to the supports of the second turret; means to eject the spools from the supports of the second turret and discharge the spools from the apparatus and means to intermittently and simultaneously rotate the first and second turrets to position the supports of the first turret relative to the means to assemble a spool on said supports and the spool transferring means, and position the supports of the second turret relative to the 20 spool transferring and ejecting means.

20 9. In apparatus for making sheet metal spools, a rotatable turret carrying a series of supports equidistantly spaced about and extended radially from the turret; means to successively engage a flange on each of the supports, engage a core on the supports with one end of the core engaging the flange on the supports, engage a second flange on the opposite end of the core on the supports and crimp end portions of the core with the 25 flanges to form a spool; a second rotatable turret carrying a series of supports equidistantly spaced about and extended radially from said second turret; means to transfer the formed spools from the supports of the first turret to the supports of the second turret; means to form an inwardly extending tongue in the core of the spools on the supports of the second turret; means to eject the spools having the tongues from the supports of the second turret; and means to intermittently and simultaneously rotate the first and second turrets to position the supports of the first turret relative to the means to assemble a spool on said supports and the spool transferring means, and position the supports of the second turret relative 30 to the spool transferring, tongue forming, and spool ejecting means.

30 10. In apparatus for making sheet metal spools, a rotatable turret carrying a series of radially extending horns, each horn having a reduced portion at the outer end to support a core and flanges at the opposite ends of the core, a die arranged in the shoulder of the horn formed by the reduced portion thereof, means to intermittently rotate the turret to successively position the horns at predetermined stations, and a die supported at a predetermined station to have movement toward and away from the reduced portion of a horn at said station and co-operate with the die of said horn to crimp the opposite ends of the core with the flanges and form a spool.

35 11. In apparatus for making sheet metal spools, a rotatable turret carrying a series of radially extending horns, each horn having a reduced portion at the outer end to support a core and flange at the opposite ends of the core, a die arranged in the shoulder of the horn formed by the reduced portion thereof, means to intermittently rotate the turret to position the horns at successive stations, a die supported at one of said stations to have movement toward and away from the reduced portion of a horn at said station and co-operate with the die of said horn to crimp the opposite ends of the core with the flanges and form a spool, and complemental members mounted at the station at which the die is supported to have movement toward and away from opposite portions of a core supported on the reduced portion of the horn and adapted to engage the core previously to the movement of the die toward the horn, said complemental members being of a length to maintain the flanges in predetermined spaced relation during the crimping of the core ends with the flanges.

40 12. Apparatus for making sheet metal spools as claimed in claim 11, wherein the complemental members are arranged to have yielding movement longitudinally of the core to permit movement of the core toward the die in the horn and the crimping of the end of the core adjacent said die.

45 13. In apparatus for making metal spools, a rotatable turret carrying a series of radially extending horns, a pair of hoppers mounted on diametrically opposite sides of the turret and adapted to support flanges in stack formation, a support arranged to engage the periphery of a flange and mounted between each hopper and the turret to position the flange in axial alignment with the horns, means to transfer flanges from the hoppers to the supports, means to transfer flanges from the supports and engage said flanges on the horns, and means to simultaneously actuate both flange transferring means of each hopper and support.

50 14. In apparatus for making sheet metal spools, a rotatable turret carrying a series of radially extending horns, means to intermittently rotate the turret to position the horns at successive stations, a pair of hoppers mounted at diametrically opposite stations adapted to support flanges in stack formation, a pair of supports arranged to engage the periphery of the flanges and mounted between the hoppers and the horns at said diametrically opposite stations to position the flanges in alignment with the horns at said stations, means to transfer the lowermost flange in each hopper to the supports, means to transfer the flange in each support and engage it in the 55 supports.

55 15. In apparatus for making sheet metal spools, a rotatable turret carrying a series of radially extending horns, each horn having a reduced portion at the outer end to support a core and flanges at the opposite ends of the core, a die arranged in the shoulder of the horn formed by the reduced portion thereof, means to intermittently rotate the turret to successively position the horns at predetermined stations, and a die supported at a predetermined station to have movement toward and away from the reduced portion of a horn at said station and co-operate with the die of said horn to crimp the opposite ends of the core with the flanges and form a spool.

60 16. In apparatus for making sheet metal spools, a rotatable turret carrying a series of radially extending horns, each horn having a reduced portion at the outer end to support a core and flange at the opposite ends of the core, a die arranged in the shoulder of the horn formed by the reduced portion thereof, means to intermittently rotate the turret to position the horns at successive stations, a die supported at one of said stations to have movement toward and away from the reduced portion of a horn at said station and co-operate with the die of said horn to crimp the opposite ends of the core with the flange and form a spool, and complemental members mounted at the station at which the die is supported to have movement toward and away from opposite portions of a core supported on the reduced portion of the horn and adapted to engage the core previously to the movement of the die toward the horn, said complemental members being of a length to maintain the flange in predetermined spaced relation during the crimping of the core ends with the flange.

65 17. In apparatus for making sheet metal spools, a rotatable turret carrying a series of radially extending horns, each horn having a reduced portion at the outer end to support a core and flange at the opposite ends of the core, a die arranged in the shoulder of the horn formed by the reduced portion thereof, means to intermittently rotate the turret to position the horns at successive stations, a die supported at one of said stations to have movement toward and away from the reduced portion of a horn at said station and co-operate with the die of said horn to crimp the opposite ends of the core with the flange and form a spool, and complemental members mounted at the station at which the die is supported to have movement toward and away from opposite portions of a core supported on the reduced portion of the horn and adapted to engage the core previously to the movement of the die toward the horn, said complemental members being of a length to maintain the flange in predetermined spaced relation during the crimping of the core ends with the flange.

70 18. In apparatus for making sheet metal spools, a rotatable turret carrying a series of radially extending horns, each horn having a reduced portion at the outer end to support a core and flange at the opposite ends of the core, a die arranged in the shoulder of the horn formed by the reduced portion thereof, means to intermittently rotate the turret to position the horns at successive stations, a die supported at one of said stations to have movement toward and away from the reduced portion of a horn at said station and co-operate with the die of said horn to crimp the opposite ends of the core with the flange and form a spool, and complemental members mounted at the station at which the die is supported to have movement toward and away from opposite portions of a core supported on the reduced portion of the horn and adapted to engage the core previously to the movement of the die toward the horn, said complemental members being of a length to maintain the flange in predetermined spaced relation during the crimping of the core ends with the flange.

75 19. In apparatus for making sheet metal spools, a rotatable turret carrying a series of radially extending horns, each horn having a reduced portion at the outer end to support a core and flange at the opposite ends of the core, a die arranged in the shoulder of the horn formed by the reduced portion thereof, means to intermittently rotate the turret to position the horns at successive stations, a die supported at one of said stations to have movement toward and away from the reduced portion of a horn at said station and co-operate with the die of said horn to crimp the opposite ends of the core with the flange and form a spool, and complemental members mounted at the station at which the die is supported to have movement toward and away from opposite portions of a core supported on the reduced portion of the horn and adapted to engage the core previously to the movement of the die toward the horn, said complemental members being of a length to maintain the flange in predetermined spaced relation during the crimping of the core ends with the flange.

horn at said support, and means to simultaneously actuate both flange transferring means at each of said diametrically opposite stations.

15. In apparatus for making sheet metal spools as claimed in claim 14, means to yieldingly engage opposite portions of the flanges in the supports and maintain said flanges in position to be engaged on the horns.

16. Apparatus for making sheet metal spools 10 as claimed in claim 14, wherein the means to transfer the flanges from the hoppers to the supports comprises a slide having a bifurcation at one end to engage the lowermost flange in the hopper and an intermediate portion to support the flanges in the hopper during the transfer of the lowermost flange to the supports.

17. Apparatus for making sheet metal spools 20 as claimed in claim 14, wherein the supports for the flanges comprises standards mounted in alignment with the horns at the diametrically opposite stations and arranged with rectangular recesses in the vertical faces thereof, and plates mounted to span said recesses and having an elongated opening therein in alignment with the recesses 25 with a circular portion at one end thereof in horizontal alignment with the horns.

18. In apparatus for making sheet metal spools as claimed in claim 14, standards mounted at the diametrically opposite stations of the horns and 30 arranged with tubular portions extending in the plane of the axis of the horns, the means to transfer the flanges from the supports to the horns comprising plungers slidably supported in the tubular portions of the standards.

35. 19. In apparatus for making sheet metal spools, a rotatable turret carrying a series of radially extending horns, means to intermittently rotate the turret to position the horns at successive stations, a pair of standards mounted at diametrically opposite stations of the horns, each standard having a horizontally extending slideway at the upper portion thereof and a tubular portion extending parallel of and below the slideway, a hopper mounted on each standard 40 above the slideway adapted to support flanges in stack formation with the lowermost flange in the plane of the slideway, a pocket arranged in the face of each standard in communication with the hopper of said standard to receive flanges from said hopper, a slide mounted in each slideway adapted to engage the lowermost flange and move 45 said flange to the pocket, a plunger slidably mounted in the tubular portion of each standard adapted to engage a flange supported in the pocket and move said flange onto a horn positioned 50 relative to each of the standards, and a lever pivotally supported on each standard pivotally connected to the slide and plunger and adapted to 55 actuate the slide and plunger to move flanges simultaneously during a period of rest of the turret.

60. 20. In apparatus for making sheet metal spools, a rotatable turret carrying a series of radially extending horns, means to intermittently rotate the turret to position the horns at successive stations, hoppers at diametrically opposite stations adapted to support flanges in flat stack formation, a support for a plurality of cores mounted at a station intermediate the hoppers, reciprocatory members arranged to engage the cores on the support therefor and advance said cores along said support into engagement with the horn at said intermediate station, means to position flanges on the horns 65 at the hopper stations, means to transfer flanges

from the hoppers to the flange positioning means, means to actuate the flange positioning and transferring means, means to couple the actuating means with the flange transferring means, said coupling means being normally urged out 5 of coupling position, means adapted to engage and position the coupling means to connect the actuating means with the flange transferring means, and means mounted on the reciprocatory members to be engaged by spaced cores on the 10 support therefor and adapted by the engagement of the cores therewith to actuate the means to engage and position the coupling means to connect the actuating means with the flange transferring means and transfer the flanges to 15 the positioning means to be positioned on the horns at the hopper stations.

21. In apparatus for making sheet metal spools, a rotatable turret carrying a series of radially extending horns, means to intermittently 20 actuate the turret to position the horns at successive stations, hoppers at diametrically opposite stations of the horns adapted to support spool flanges in flat stack formation, a support for spool cores mounted at a station of the horns 25 intermediate the hopper stations, a series of reciprocatory fingers yieldingly urged to engage the rear edges of the cores on the support and advance said cores on the support into engagement with the horn positioned at said intermediate station, a slide operative relative to each hopper to feed flanges from the hoppers relative to the horns at said hopper stations, reciprocatory means adapted to actuate the slide toward and away from the hoppers, a latch pivotally mounted on each of said slides arranged 30 to engage and couple the slide actuating means to the slides and yieldingly urged out of coupling position, means adapted to engage and position the latches in engagement with the slide actuating means; means mounted relative to and movable with spaced fingers of the series of core advancing fingers adapted to engage the cores on the core support during the core advancing 35 movement of the fingers, and engage and actuate the latch positioning means when engaged by the cores, the engagement of said actuating means movable with the fingers with cores on the core support actuating the latch positioning means to position the latch in engagement with 40 the slide actuating means whereby the slide is actuated, and the absence of cores on the core support in the path of the fingers causing the means movable with the fingers to move out of engagement with the latch positioning means 45 and effect normal positioning of the latch out of engagement with the slide actuating means to prevent the actuation of the slides.

22. In apparatus for making sheet metal spools, a rotatable turret carrying a series of radially extending horns, means to intermittently 50 rotate the turret and position the horns at successive stations, a cylindrical support for spool cores mounted at one of said stations and having diametrically opposite slots, a reciprocatory 55 slide mounted to have movement longitudinally of the cylindrical support, and fingers pivotally mounted on the slide and yieldingly positioned to extend through the slots in the cylindrical support to engage and advance the cores along 60 the cylindrical support by the movement of the slide toward the turret, the fingers on the forward portion of the slide engaging a core on a horn at said station by said movement of the 65 slide.

23. In apparatus for making sheet metal spools, a rotatable turret carrying a series of radially extending horns, means to intermittently rotate the turret to position the horns at successive stations, a plunger mounted at the initial station and reciprocated toward said horn to engage a spool flange thereon, a pair of reciprocatory fingers at a succeeding station adapted to engage a spool core on the horn positioned at said station with the forward end of the core engaging the flange on said horn, and a second plunger mounted at a succeeding station and reciprocated toward the horn at said succeeding station to engage a second flange on the rearward end of the core and arranged to flare outwardly the rearward edge portion of the core subsequently to the engagement of the second flange on the core to retain said second flange on the core during the rotation of the turret to the remaining succeeding stations.
24. In apparatus for uniting flanges to a core to form a sheet metal spool, a rotatable turret carrying a horn arranged with an annular die and adapted to support a core and flanges at the opposite end portions of the core with the inner end of the core in registry with the annular die, means to intermittently rotate the turret to position the horn at successive stations, an annular die reciprocally mounted at one of said stations to have movement toward and away from the turret and arranged during the forward movement thereof to engage the outer end of the core and force the inner end of the core against the die on the horn to crimp the end portions of the core with the flanges, and annular members slidably carried by the horn and reciprocatory die and yieldingly positioned to extend in front of the die of the horn and the face of the reciprocatory die to engage the flanges and strip the core and flanges from the dies.
25. In apparatus for making sheet metal spools, a rotatable turret carrying a series of radially extending horns, means to intermittently rotate the turret to position the horns at successive stations, means at the initial station to position a flange on the horns, means at a succeeding station to position a core on the horns with an end portion of the core in engagement with the flange on the horns, means at a succeeding station to position a second flange on the opposite end portion of the core on the horns, means at a succeeding station to crimp the opposite ends of the core with the flanges to form a spool on the horns, and means at a succeeding station to remove the formed spool from the horns, the means to remove the formed spool from the horns being actuated by the turret rotating means.
26. In apparatus for making sheet metal spools, a rotatable turret carrying a series of radially extending horns adapted to support a spool thereon, means to intermittently rotate the turret to position the horns at successive stations, a second rotatable turret carrying a series of radially extending horns adapted to be positioned intermittently in alinement with horns of the first turret at the last station thereof by the rotation of the first turret, reciprocatory means having movement longitudinally of the horns of the first and second turrets at the last station of the first turret to transfer the spools from the horns of the first turret to the horns of the second turret, a punch reciprocatory toward and away from the horns of the second turret to form inwardly extending tongues in the cores of the spools on the horns of the second turret, and reciprocatory means actuated to engage a flange of the spools having the tongues in the cores thereof on the horns of the second turret and remove said spools from said horns.
27. In apparatus for making sheet metal spools, a rotatable turret carrying a series of radially extending horns, means to intermittently rotate the turret and position the horns at successive stations, means at the initial station of the horns to engage a flange on the horns, means at a succeeding station to engage a core on the horns in engagement with the flange on the horns, and means extending in the path of movement of the horns between said stations to prevent the expelling of the flanges from the horns by centrifugal force caused by the rotation of the turret.
28. In apparatus for making sheet metal spools, a rotatable turret carrying a series of radially extending horns, means to intermittently rotate the turret to position the horns at successive stations, means at the initial station to feed and engage a flange on the horns and the feeding means being normally inoperative to feed flanges to the flange engaging means, means at a succeeding station to intermittently feed cores toward the turret and engage a core on the horns with one end of the core in engagement with the flange on the horns, means at another succeeding station to feed and engage a second flange on the opposite end of the core on the horns and the feeding means being normally inoperative to feed flanges to the flange engaging means, means arranged along the path of travel of the cores toward the turret and operative by a core at a predetermined distance from a horn at the core engaging station to render operative the flange feeding means to feed a flange to the flange engaging means to engage the first flange on the horns, and means arranged at the position of the core to be engaged on the horn and operative by said core to render operative the flange feeding means to feed a flange to the flange engaging means to engage the second flange on the horns.
29. Apparatus for making sheet metal spools as claimed in claim 21, wherein the means adapted to engage and position the latch in engagement with the slide actuating means, comprises a shaft rotatably mounted between the flange hoppers and the core support, an arm fixed to one end of the shaft to engage the latch, a second arm fixed to the opposite end of the shaft, and a third arm pivotally mounted at one end below the shaft connected intermediate the ends thereof with the second arm and having means at the opposite end to engage the core engaging means.
30. Apparatus for making sheet metal spools as claimed in claim 22, wherein the cylindrical core support comprises a pair of complementary semi-circular members, one of said members being fixedly mounted, and the other member movably mounted and adapted to be adjusted a predetermined distance from the fixed member to provide the diametrically opposite slots and to be positioned away from the fixed member for an inspection of the cores.
31. In apparatus for making sheet metal spools as claimed in claim 26, resilient means mounted to engage the spools on the horns of the second turret and position said spools in alinement with the punch.
32. Apparatus for making sheet metal spools as claimed in claim 26, a member having a cam face and mounted adjacent the periphery of the second turret intermediate the punch and the

reciprocatory means to remove the spool from the horns of said second turret, and said cam face being adapted to engage a flange of a spool on a horn of the second turret and move said spool along said horn to a position to be engaged by the reciprocatory means.

33. In apparatus for making sheet metal spools, a rotatable turret carrying a series of radially extending horns, a pair of hoppers mounted on diametrically opposite sides of the turret and adapted to support flanges in stack formation, a support mounted between each hopper and the turret and arranged to engage the periphery of a flange and position the flange in axial alignment with the horns, means to transfer the flanges from the hoppers to the supports, and means to engage the flanges in the supports and transfer said flanges to the horns.

34. In apparatus for making sheet metal spools, a rotatable support, means to engage a flange on the support, a longitudinal support for cores, means to feed cores along said longitudinal support, and

means to support and engage a core on the rotatable support with an end portion of the core in engagement with the flange on the rotatable support, means to engage a second flange on the opposite end of the core on the rotatable support, means mounted relative to both of the flange engaging means adapted to feed flanges to said flange engaging means and normally rendered inoperative, means to crimp the opposite ends of the core with the flanges to form a spool on the rotatable support, means to eject a formed spool from the rotatable support, means to actuate the rotatable support to successive positions relative to the flange engaging means, the longitudinal support, the crimping means and the ejecting means, and means adapted to be actuated by the cores on the longitudinal support to render operative the flange feeding means to position flanges relative to the flange engaging means to be engaged on the rotatable support and core by the flange engaging means.

JOHN A. JOHNSON.
